UNITED STATES PATENT OFFICE.

AARON RAUCHBACH, OF NEWARK, NEW JERSEY, ASSIGNOR TO THE RAUCHBACH-GOLDSMITH CO., A CORPORATION OF NEW JERSEY.

INTERIOR TRUNK-LOCK MECHANISM.

Application filed January 16, 1926. Serial No. 81,661.

This invention relates, generally, to improvements in interior locking mechanism for trunks and the like; and the invention has reference, more particularly, to a novel construction of interior locking mechanism which is especially suitable for securing together the body sections of wardrobe trunks.

This invention has for its principal object to provide in combination with locking means, adapted to securely fasten hinged trunk sections together at a plurality of points within the interior thereof, of a novel means for actuating the same, which is co-operatively associated with the ordinary hasp and key lock devices of the trunk in such novel manner, as to be concealed when the latter are in operative interlocked relation, so that access thereto for manipulation cannot be attained except upon unlocking and opening said hasp and key lock devices.

Another object of this invention is to provide an interior locking mechanism which, although its actuating elements are arranged to be concealed by the interlocking hasp and key lock devices of the trunk, are nevertheless mechanically independent thereof and subject to independent manipulation, so that said interior locking mechanism may be employed in combination with hinged hasp and key lock device of the ordinary type.

Other objects of this invention, not at this time more particularly enumerated, will be clearly understood from the following detailed description of the same.

With the objects of this invention in view, the same consists, primarily, in the novel interior locking mechanism for trunks herein-after set forth; and, furthermore, the invention consists in the novel arrangements and combinations of the various devices and parts, as well as in the details of the construction of the same, all of which will be hereinafter more fully described, and then embodied in the appended claims.

The invention is clearly illustrated in the accompanying drawings, in which:

Figure 1 is a perspective view of a trunk equipped with the novel interior locking mechanism made according to and embodying the principles of this invention, the trunk sections being shown unlocked and standing in opened position; Figure 2 is a vertical section, showing the trunk sections closed together and secured by the novel interior locking mechanism; Figure 3 is a

vertical section, taken on line 3—3 in Figure 2, with the hinged hasp of the key lock operatively interengaged to conceal the actuating means of the interior locking mechanism; Figure 4 is a sectional view similar to that shown in Figure 3, but with the hinged hasp opened, and the actuating means withdrawn and manipulated to release said interior locking mechanism; Figure 5 is a fragmentary horizontal section, taken on line 5—5 in Figure 3, and drawn on an enlarged scale; Figure 6 is a fragmentary sectional perspective, on an enlarged scale, showing the relation of the actuating means to the interior locking mechanism; Figure 7 is a detail enlarged end view of the actuating mechanism in position to move the interior locking mechanism to operative locked position; and Figure 8 is a similar view showing the actuating mechanism in position to release the interior locking mechanism; and Figure 9 is a side face elevation and Figure 10 a front edge elevation of the locking bar of the interior locking mechanism.

Similar characters of reference are employed in all of the hereinabove described views, to indicate corresponding parts.

Referring now to said drawings, the reference character 11 indicates one body section and 12 the other body section of a trunk of the wardrobe type, said sections being suitably hinged together in the usual manner so that the same may be swung apart to disclose the interior fittings and content. Secured to the outer face of the body section 11, adjacent to its meeting edge portion 13, is the base plate 14 of a suitable main or exterior locking element 15; and hingedly secured in corresponding position to the outer face of the body section 12, adjacent to its meeting edge portion 16, is a swinging hasp 17 provided with a suitable locking element 18 for cooperation with said opposite exterior locking element 15. Said cooperative locking elements 15 and 18 are constructed for actuation and control by a key in any suitable manner commonly employed in connection with exterior hasp locks.

Disposed on the interior side of the meeting edge portion 13 of said trunk section 11, in parallel relation thereto, is an interior locking bar 19. This locking bar 19 is slidably mounted in guide yokes 20, which are fastened to the body section 11, so that the locking bar 19 is capable of longitudinal

movement therethrough. Suitably affixed to the interior side of the meeting edge portion 16 of the opposite trunk section 12, are laterally projecting lock-tongues 21, which extend beyond the trunk section 12 so as to enter the trunk section 11, when the latter is closed relatively to the former, and which are thus respectively positioned to cooperatively interlock with opposite ends 10 of said locking bar 19, upon proper actuation of the latter. Said lock-tongues are provided in the upper marginal portions thereof adjacent to their free ends, with indented portions or notches 22 adapted to 15 form female locking elements. Said locking bar 19 is provided in its outer longitudinal marginal edge portion, adjacent to each end thereof, with somewhat elongated indented portions or notches 23, provided 20 at their upper ends with downwardly projecting lugs 24 in the plane of said locking bar, and adapted to form male locking elements which, by a proper downward movement 25 of the locking bar 19 may be respectively entered in the female locking elements provided by the indented portions or notches 22 of the lock-tongues 21. The opposed meeting faces of the indented portions or notches 22 and lugs 24 are correspondingly 30 chamfered or inclined so that, when the latter are entered into the former by the downward movement of the locking bar 19, a wedge-like cooperation thereof is effected tending to draw the meeting edges 13 and 35 16 of the respective trunk sections 11 and 12 tightly together, when the same are closed and locked. The length of said indented portions or notches 23 of said locking bar 19 is such as to permit, on upward movement 40 of the latter, the lugs 24 to retract freely from the indented portions or notches 22 of the lock tongues 21, so that said lock tongues 21 may withdraw laterally from the indented portions or notches 23, when swinging 45 the body sections 11 and 12 of the trunk to open position.

Secured to the interior side of the marginal portions of the trunk section 11, so as to be disposed respectively on opposite sides of said locking-bar 19 and intermediate the upper and lower ends thereof, are bracket members 25 between the ends of which is mounted a transverse fulcrum pin 26. Pivoted on said fulcrum pin 26 is an actuating lever 27, which extends forwardly 50 through a slot 28 provided in said locking bar 19 with its outer end projecting through the wall of said trunk section 11, and thence through a vertical slot 29 provided in said base plate 14 of the main or exterior locking element 15. Said slot 29 is of sufficient length to permit of operative up and down swinging movements of said actuating lever 27. The outer end of said actuating lever 27 is preferably doubled on

itself to provide a knuckle or bearing 30 for the attachment thereto of a ring or loop 31, such construction also providing a double thickness of body, as at 32, adjacent to the outer end thereof. The pivotal connection of said actuating lever 27 with the fulcrum pin 26 is provided by a longitudinal slot 33 through which the latter passes. This slot 33 permits inward and outward longitudinal movement to be imparted to said lever 27 in addition to the swinging movement thereof on the fulcrum pin. Normally, the lever 27 is thrust longitudinally inward so that its outer end with the loop or ring 31 is positioned close against the base plate 14 of the main or exterior locking element 15. When the trunk sections 11 and 12 are in open relation, the locking bar 19, being raised by an upward swing of the outdrawn lever 27, is thus positioned so that open lower ends of the indented portions or notches 23 are in lateral alignment with the ends of the lock-tongues 21. With the parts in such positions, the body sections 11 and 12 may be swung together into closed relation, and by this movement the ends of the locking tongues 21 of the section 12 are caused to enter the indented portions or notches 23 of said locking bar 19. To lock the closed trunk sections together, the operator now swings downwardly the lever 27, which transmits to the locking bar a downward longitudinal movement, serving to carry the lugs 24 thereof into the notches 22 of said lock-tongues 21, thus interlocking the parts together. After the locking-bar 19 is thus disposed in locked relation to the lock-tongues 21, the actuating lever 27 is thrust longitudinally inward until its doubled outer end portion 32 is caused to enter a widened portion 34 of the slot 29 which is provided in the base plate 14, thereby engaging a portion of said lever beneath the shoulder 35 provided by said widened slot 100 portion 34. By this means the lever 27 is held against upward swinging movement, and in turn holds the locking-bar 19 against accidental longitudinal displacement from its operative locking position. At the same 105 time the main body of the actuating lever 27 is moved into the trunk interior out of the way, its loop or ring 31 being laid over on to the base plate 14. The operator now swings the hasp 17 of the key lock means 110 over upon the base plate 14, so that said hasp covers and conceals the outer end of the actuating lever, while at the same time the cooperative locking elements 15 and 18 may be interengaged and operatively locked 115 together by means of a proper key. It will thus be apparent, that the locked hasp 17 will both conceal the actuating lever 27, and at the same time prevent unauthorized access thereto or tampering therewith, and 120

125 130

consequently the locking bar 19 cannot be released from locking position until the hasp 17 is unlocked and swung back to expose said actuating lever 27 for manipulation.

5 When the hasp 17 is unlocked and swung back, the operator grasps the ring or loop 31, by means of which the actuating lever may be drawn longitudinally outward to normal operative position, whereupon its 10 doubled portion 32 is released from the shoulder 35, and the lever may be thereupon swung upward to thus raise the locking-bar 19 to release the lugs 24 of the latter from interlocked engagement with the notches 22 15 of the locking tongues 21, so that the trunk sections 11 and 12 may be swung apart to opened relation.

From the above description, it will be apparent that this invention provides a comparatively simple interior locking mechanism for trunks which, while being independently manipulatable, is nevertheless concealed by the ordinary exterior hasp lock mechanism so that it cannot be tampered 25 with when the trunk is in locked condition. The construction and arrangement is such that ordinary hinged hasp lock mechanism may be employed, and, furthermore, such hasp lock mechanism is not subjected to 30 strains and likelihood of disorder consequent on constructions wherein the hasp lock mechanism also forms a manipulative part of the interior locking mechanism.

I am aware that some changes may be 35 made in the various arrangements and combinations of the several devices and parts of my novel interior trunk lock mechanism, without departing from the scope of this invention as above described and as defined 40 in the appended claims. Hence, I do not limit my invention to the exact arrangements and combinations of the various devices and parts as described in the foregoing specification, nor do I confine myself to the exact 45 details of the construction of said parts as illustrated in the accompanying drawings.

I claim:—

1. In combination with a pair of hinged trunk sections, a plurality of locking tongues 50 secured to the inner side of one trunk section to extend into the opposite trunk section when said sections are closed, a longitudinally movable locking-bar mounted on the inner side of said opposite trunk section, said locking tongues and locking bar having 55 mutually interengageable parts adapted to be operatively engaged by movement of said locking-bar in one direction, an actuating lever engaged with said locking-bar, means 60 for pivoting said lever for vertical swinging movement, an exterior stationary lock-plate on said opposite trunk section provided with a slot through which the outer end of said actuating lever projects, said actuating lever 65 being longitudinally slid able on its fulcrum

for endwise movement into the trunk interior, and an exterior hinged key lock hasp on said first mentioned trunk section movable into engagement with said lock plate of said opposite section, and into overlying and 70 concealing relation to the outer end of said actuating lever when the latter is moved to inwardly thrust position.

2. In combination with a pair of hinged trunk sections, a plurality of locking tongues 75 secured to the inner side of one trunk section to extend into the opposite trunk section when said sections are closed, a longitudinally movable locking-bar mounted on the inner side of said opposite trunk section, 80 said locking tongues and locking-bar having mutually interengageable parts adapted to be operatively engaged and disengaged by reciprocative movement of said locking bar, an interior bracket means having a fulcrum pin disposed intermediate the ends of said locking bar, an actuating lever having its outer end projected exteriorly from the trunk body, said actuating lever having a slotted inner end engaged with said fulcrum pin whereby said lever is capable of 85 both swinging movement and endwise movement, means for engaging said lever with said locking-bar, and an exterior key lock means 90 for said trunk sections having a hinged hasp member adapted when in locked position to overlie and conceal the outer end of said actuating lever.

3. In combination with a pair of hinged trunk sections, a plurality of locking tongues secured to the inner side of one trunk section to extend into the opposite trunk section when said sections are closed, a longitudinally movable locking-bar mounted on the inner side of said opposite trunk section, said locking tongues and locking-bar having mutually interengageable parts adapted to be operatively engaged and disengaged by reciprocative movement of said locking-bar, an interior bracket means having a fulcrum pin disposed intermediate the ends of said locking-bar, an actuating lever having its outer end projected exteriorly from the trunk body, said actuating lever having a slotted inner end engaged with said fulcrum pin whereby said lever is capable of both swinging movement and endwise movement, means for engaging said lever with said locking-bar, an exterior key lock means for said trunk sections having a hinged hasp member adapted when in locked position to overlie and conceal the outer end of said actuating lever, and means 110 for retaining said actuating lever against locking-bar releasing movement.

4. In combination with a pair of hinged trunk sections, a plurality of locking tongues secured to the inner side of one trunk section to extend into the opposite trunk section when said sections are closed, a longi- 130

itudinally movable locking-bar mounted on the inner side of said opposite trunk section, said locking tongues and locking-bar having mutually interengageable parts adapted to be operatively engaged and disengaged by reciprocative movement of said locking bar, an interior bracket means having a fulcrum pin disposed intermediate the ends of said locking-bar, an actuating lever having its outer end projected exteriorly from the trunk body, said actuating lever having a slotted inner end engaged with said fulcrum pin whereby said lever is capable of both swinging movement and endwise movement, an exterior stationary lock-plate on said opposite trunk section provided with a slot through which the outer end of said actuating lever projects, and an exterior hinged key lock hasp on said first mentioned trunk section movable into engagement with said lock plate of said opposite section, and into overlying and concealing relation to the outer end of said actuating lever when the latter is moved to inwardly thrust position.

5. In combination with a pair of hinged trunk sections, a plurality of locking tongues secured to the inner side of one trunk section to extend into the opposite trunk section when said sections are closed, a longitudinally movable locking-bar mounted on the inner side of said opposite trunk section, said locking tongues and locking-bar having mutually interengageable parts adapted to be operatively engaged and disengaged by reciprocative movement of said locking bar, an interior bracket means having a fulcrum pin disposed intermediate the ends of said locking-bar, an actuating lever having its outer end projected exteriorly from the trunk body, said actuating lever having a slotted inner end engaged with said fulcrum pin whereby said lever is capable of both swinging movement and endwise movement, an exterior stationary lock-plate on said opposite trunk section provided with a slot through which the outer end of said actuating lever projects, an exterior hinged key lock hasp on said first mentioned trunk section movable into engagement with said

lock plate of said opposite section, and into overlying and concealing relation to the outer end of said actuating lever when the latter is moved to inwardly thrust position, said actuating lever and exterior lock-plate having mutually cooperative means for retaining the former against locking-bar releasing movement when in inactive inwardly thrust position.

6. In combination with a trunk having a pair of hinged sections provided with internal cooperative locking means, comprising a stationary means on one trunk section and a movable means on the opposite trunk section, a pivoted lever means for actuating said movable internal locking means having its outer end externally projected from the trunk, said lever being longitudinally movable for outward extension from the trunk so as to be subject to manipulation but inwardly thrust when inactive, and an exterior key lock means for said trunk sections having a hinged hasp member adapted when in locked position to overlie and conceal the outer end of the inwardly thrust lever.

7. In combination with a trunk having a pair of hinged sections provided with internal cooperative locking means, comprising a stationary means on one trunk section and a movable means on the opposite trunk section, a pivoted lever means for actuating said movable internal locking means having its outer end externally projected from the trunk, said lever being longitudinally movable for outward extension from the trunk so as to be subject to manipulation but inwardly thrust when inactive, an exterior key lock means for said trunk sections having a hinged hasp member adapted when in locked position to overlie and conceal the outer end of the inwardly thrust lever, and means for retaining said lever against swinging movement when inwardly thrust to internal lock actuating position.

In testimony that I claim the invention set forth above I have hereunto set my hand this 1st day of December, 1925.

AARON RAUCHBACH.
